Patented Dec. 25, 1962

194,276

CANISTER FOR TEA

Michael Saphier, New York, N.Y., assignor to Lincoln Metal Products Corporation, Brooklyn, N.Y., a corporation

Filed Feb. 12, 1962, Ser. No. 68,776

Term of patent 14 years

(Cl. D44—6)

The FIGURE is a perspective view of a canister for tea showing my new design, the essential features thereof being shown in full lines.

I claim:

The ornamental design for a canister for tea, substantially as shown and described.
